UNITED STATES PATENT OFFICE

JOHN W. KABITZKE, OF CHICAGO, ILLINOIS

INTERNAL COMBUSTION ENGINE

Application filed April 11, 1928, Serial No. 269,045. Renewed February 9, 1931.

The invention relates to internal combustion engines and more particularly to engines of this character which are of the two-cycle type.

5 One object of the present invention is to provide a two-cycle internal combustion engine which consists of a minimum number of operating parts and is simple in construction in that it dispenses with separately operable or independent valves.

10 Another object of the invention is to provide an engine of the aforementioned type embodying a fan which is mounted on the crank shaft and is operative to draw gaseous 15 fuel from a carburetor and force it under pressure to the intake ports for the combustion chamber.

15 A further object of the invention is to provide an internal combustion engine which is 20 of new and improved construction and is efficient in operation.

25 Other objects will be apparent from the following detailed description.

The invention consists in the several novel 30 features hereinafter set forth and more particularly defined by the claims at the conclusion hereof.

35 In the drawings which accompany and form a part of this specification or disclosure 30 and in which like numerals of reference denote corresponding or like parts throughout the several views:

40 Figure 1 is a longitudinal section of an engine embodying the invention, showing the piston at the end of its down or power stroke and the intake and exhaust ports in their open position;

45 Figure 2 is a view similar to Figure 1, showing the piston in its alternative position and the intake and exhaust ports closed;

50 Figure 3 is a transverse section taken on line 3—3 of Figure 1;;

55 Figure 4 is a cross section taken on line 4—4 of Figure 1; and

60 Figure 5 is a cross section taken on line 5—5 of Figure 1.

65 The invention is exemplified in an internal combustion engine of the two-cycle type comprising a shaft 6 which is carried by a crank-case 7 consisting of an upper section 8 and

a lower section 9; a casing 10 having a cylinder 11 formed therein; and a piston 12 which is mounted to slide in the cylinder 11 and is connected by a pitman 13 to a crank 14 on the shaft 6. The casing 10 and the 55 crank-case 7 are connected together in superposed relation by bolts 15^a which extend through abutting flanges 15 which are formed on the members respectively. The crank-shaft is journalled in a pair of bearings 16 60 which are mounted in semi-cylindrical sockets 17. The latter are cast in the contiguous parts of the end walls of the case-sections 8 and 9. A fly wheel 18 is fixedly secured to one end of the shaft 6 by a key 19 or any other 65 suitable means.

The casing 10 consists of an inner wall 20 and an outer wall 21. The latter extends from the top of the casing to the lower central portion and is spaced from the wall 20 70 by a bottom wall 22 to form an annular water jacket 10^a around the cylinder 11. The top of the casing is closed by a head 23 which consists of an outer cylindrical wall 24 and an inner wall 25. These last mentioned 75 walls extend longitudinally into the working cylinder and are spaced apart to form a water jacket 26. The wall 23 is spaced inwardly from the wall 20 and the upper end thereof extends outwardly and fits against the top wall 27 which joins the casing walls 20 and 21. The upper end of the inner wall 80 of head 23 extends outwardly and is connected to the marginal portion of the outer wall by an integral connecting member or 85 web 28. The head is held in place by means of bolts 29 which are anchored or threaded to the upper cross wall 27. The latter and the contiguous marginal portion of the wall 24 have registering openings formed there- 90 in so that the jackets 10^a and 26 communicate with each other. Water is circulated 95 through these jackets in any suitable manner so as to prevent the casing 9 from becoming overheated. The lower ends of the walls 24 and 25 extend inwardly to form the top ele- 100 ment 30 of the combustion chamber. A spark plug 31 for igniting the fuel in said chamber extends through and is threaded to this element.

A series of fuel inlet ports 32 are formed in the upper portion of the casing beneath the lower extremity of the head 23. Fuel is forced under pressure into the combustion chamber through these ports by means of a fan wheel 33 which is mounted on one end of the shaft 6. This fan operates in a cylindrical casing 34 which is supported in place from the crank-case 7 and has an inlet 35. The latter is connected by a pipe 36 to receive gaseous fuel from a carburetor (not shown) which may be of any well known or suitable construction that operates to vaporize gasoline or any other liquid fuel. The fan casing 34 is provided with an outlet 37 which is connected to the inlet ports by a conduit 38. The upper end of this conduit is in the form of a ring which extends completely around the cylinder casing. A characteristic of utilizing a conduit having a ring discharge of this character is that the gaseous fuel is heated by the water jacket as it encircles the casing prior to passing through the inlet ports. This facilitates combustion and increases the efficiency of the engine. During rotation of the crank-shaft 6, the fan-wheel 33 draws the vaporized fuel through the pipe 36 and inlet 35, compresses it by centrifugal force and then forces it under pressure to the inlet ports 32 by way of the outlet 37 and conduit 38. In this manner, the fuel is delivered under pressure to the combustion chamber.

There are preferably four fuel inlet ports 32 and these are arranged in pairs which are disposed diametrically opposite each other. Instead of the usual poppet or sleeve valves, a cylindrical skirt 39 is provided for closing the inlet ports. This skirt is formed integrally with the piston so that it reciprocates therewith. It projects upwardly from the head 40 of the piston and the upper end thereof fits around the outer wall of the head 23. The piston head 40 and the head-element 30 together with the skirt form the combustion chamber of the engine. When the piston reciprocates in response to explosions produced by the sparking of the plug 31 the skirt slides back and forth or telescopes between the outer wall 24 of the head and the adjacent portion of the casing walls 20. Inlet ports 41 are formed in the upper end of the skirt and are so positioned that they register with the ports 32 so as to permit of the entry of fuel to the combustion chamber when the piston is at the end of its power stroke (Figure 1). A packing ring 42 is provided in the outer periphery of the wall 24 to prevent the escape of gas between the skirt and head. The head 40 of the piston also has packing rings to prevent the escape of gas and to seal the cylinder 11.

A series of exhaust ports 43 are formed in the lower end of the skirt 39 and are adapted to pass into registry with exhaust ducts 44

when the piston is at the end of its down stroke. The ducts 44 are formed in the casing wall 20 beneath the bottom wall 22 and deliver the products of combustion into an exhaust ring 45 which extends around the cylinder-casing and is connected to an outlet pipe 46. In order that the pressure of the products of combustion will be released prior to the entry of the new fuel into the combustion chamber, the exhaust ports 43 and the ducts 44 are made somewhat larger at the top thereof. This arrangement causes the exhaust ports to open slightly in advance of the inlet ports. Consequently the new charge of fuel is not retarded or repulsed by the gas in the combustion chamber having an equal or greater pressure. When the piston completes its power stroke all of the ports are open momentarily and the incoming charge forces the remaining products of combustion out through the exhaust ports. The intake and exhaust ports are so formed and arranged that they are closed before the new fuel has an opportunity to escape from the combustion chamber through the exhaust ports and ducts. The small amount of burned gas that remains in the combustion chamber during the compression stroke of the piston is not sufficient to damper or retard ignition. The plug 31 is controlled to produce a spark between its electrodes at the proper instant by any suitable mechanism. There are preferably four exhaust ports 43 and these are arranged in oppositely facing pairs which are disposed out of alignment with or between the pairs of inlet ports 41 so that they will not uncover or register with the ports or ducts 32 when the piston is at the end of its up or compression stroke.

In operation, the shaft 6 is initially rotated by a starter or crank. This causes the fan-wheel 23 to draw vaporized fuel from the carburetor and force it under pressure to the inlet ports 32. While the ports 41 are momentarily in registry with the ports 32 the fuel which is under pressure by reason of the action of the fan-wheel passes to the combustion chamber. As the piston travels upwardly, the fuel is compressed between the heads 40 and 30. At the end of the compression stroke, the plug 31 is rendered operative to ignite the fuel and force the piston downwardly. As the end of the power stroke is reached the exhaust ports 43 on the skirt 39 are brought into partial registry with the ducts 44. This releases the pressure in the combustion chamber, permits the products of combustion to be exhausted through the aforementioned openings or ports, and releases the pressure in the combustion chamber, prior to the opening of the inlet ports. When the piston reaches its lowest point all of the ports are open with the result that a new charge of fuel passes into the combustion chamber. Since this charge is under pressure

it forces the burned gases towards the bottom of the skirt and out through the exhaust ports, thereby scavenging the combustion chamber. Before the new supply of gaseous fuel has an opportunity to escape the piston is started on its up stroke in response to the action of the fly-wheel 18 and shifts the ports out of registry. Since the fan-wheel 33 is mounted on the crank-shaft it is manifest 10 that as the carburetor is adjusted to increase the percentage of fuel with respect to the air and thus accelerate or increase the rotational speed of the engine, the fuel is placed under greater pressure within the fan-casing. It 15 therefore results that the pressure of the fuel is proportional to the speed of the engine.

The engine disclosed herein embodies but three moving parts. Consequently the cost of manufacture is extremely low as compared to other types of two-cycle engines. Furthermore the possibility of the engine becoming inoperative due to worn out or broken parts is materially reduced.

While the invention has been illustrated 25 in connection with a single cylinder, it is to be understood that it may be embodied in an engine of the multi-cylinder type. It should also be understood that the invention is not to be restricted to the details set forth, since 30 these may be modified within the scope of the appended claims, without departing from the spirit and scope of the invention.

Having thus described the invention, what I claim as new and desire to secure by Letters Patent, is:

1. In a two-cycle internal combustion engine, the combination of a casing-member having a cylinder formed therein and provided with means forming inlet and exhaust 40 ports communicating with said cylinder, a shaft, a piston slidable in one end of the cylinder and connected to impart rotary movement to the shaft, a head extending longitudinally into the other end of the cylinder, and a skirt-member secured to the head portion of the piston slidable around the head and forming, together with said head and head portion, a combustion chamber, said skirt-member having inlet and exhaust 45 ports formed therein to register respectively with the ports in the casing-member when the piston is at the end of its power stroke, the exhaust ports of the casing and skirt members being offset or staggered 50 relatively to the inlet ports of said members so that the ports of the skirt-member nearest the head portion of the piston are capable, during the compression stroke, of passing by the inlet and exhaust ports of the 55 casing-member without the exhaust ports of one member registering with the inlet ports of the other member.

2. In a two-cycle internal combustion engine, the combination of a casing having a 60 cylinder formed therein, a shaft, a piston

slidable in one end of the cylinder and connected to impart rotary movement to the shaft, a head extending longitudinally into the other end of the cylinder, means integral with the casing forming a fuel inlet 70 port for the cylinder adjacent and inwardly of the head, means integral with the casing forming an exhaust port for the cylinder adjacent the said one end thereof, said exhaust port being longitudinally offset with respect to the inlet port, a skirt secured to the head portion of the piston slidable around the head and forming, together with said head and head portion, a combustion chamber, said skirt having an inlet and exhaust 75 port formed therein to register respectively with the inlet and exhaust ports of the casing when the piston is at the end of its power stroke, said inlet and exhaust ports in the skirt being longitudinally offset relatively 80 to each other similarly to the ports of the casing.

Signed at Chicago, Illinois, this 31st day of March, 1928.
